ELECTRIC SWITCHING DEVICE AND
MOUNTING MEANS THEREFOR

Benjamin R. Hermann, Lanesboro, Mass., assignor to General Electric Company, a corporation of New York

Application November 30, 1937, Serial No. 177,244

14 Claims. (Cl. 200—114)

The present invention relates to electric switching devices and mounting means therefor and has for an object the provision of a simple and low cost switching device of the enclosed type 5 having improved construction and arrangement of parts and improved mounting means for installation of the device directly upon a bushing supported terminal of a transformer or like piece of electric apparatus.

10 Other objects and the details of that which I believe to be novel and my invention will become apparent from the following description and the claims appended thereto taken in conjunction with the accompanying drawing in which Fig. 1 15 illustrates a rear view of an exemplary switching device, in the form of an enclosed fuse cutout, and mounting means therefor embodying my invention; Fig. 2 is a longitudinal cross-section through the housing of the cutout showing 20 the construction and arrangement of the parts thereof; Fig. 3 is a detail view of an improved mounting bracket employed in supporting the cutout; and Fig. 4 illustrates diagrammatically the manner of mounting the cutout and bracket 25 on a transformer terminal bushing.

Referring to the drawing, 10 designates a casing of porcelain or other suitable insulating material in which is mounted an upper terminal contact 11 having spring fingers 12 adapted to 30 receive therebetween the upper terminal of a switching element, such as the terminal cap 13 of an insulating fuse holder 14. Contact 11 has also a contact finger 15, backed by a spring strip 16 arranged to bear downwardly on a fuse holder 35 terminal cap. Although a fuse holder is employed in the exemplary embodiment illustrated, it will be evident from the ensuing description that the present invention is not limited to this 40 particular form of switching element. For example, an electrically conductive switching blade may be substituted for the fuse holder if it is desired, as is sometimes the case, to employ the switching device only for connecting and disconnecting purposes without fuse protection.

45 Just beneath contact 11 is an electric creepage and gas barrier 17 formed integrally with the casing and arranged to retard the rising of arc gases from the lower end of an expulsion fuse holder, such as the one illustrated, into the space 50 around the contact 11 in the upper part of the housing. The illustrated fuse holder 14 is supported by bosses 20 and 21 formed integrally with a door 22, constructed of suitable insulation, which is adapted to close the open front of casing 10 and which has an eyelet handle 23 for

manually moving the door and fuse holder into and out of operative position. The door and fuse holder are supported in the casing by means of a hinge lever 24 one end of which is pivotally attached to door boss 21, as indicated at 25, and the other end of which has a hook-shaped portion 26 arranged to engage a hinge pin 27 carried by hinge bracket 28. The hinge lever normally is held in rigid relation to fuse holder 14 by means of a portion 36 of a fuse link extending out of the lower end of the fuse holder and secured to the lever by any suitable form of clamping means indicated at 31. With this arrangement, upon rupture of the fuse link in fuse holder 14, the door and fuse holder drop 15 downwardly and outwardly to a position wherein the fuse holder is isolated from upper contact 11, this operation being in a manner similar to that described in detail in connection with the dropout fuse cutout of my patent No. 2,081,813, issued 20 May 25, 1937, and assigned to the assignee of the present invention.

Hinge bracket 28 serves as the lower terminal contact of the cutout and forms part of an electrically conductive bolt 32 which extends outwardly through an opening in the rear wall of casing 10 and which is fixedly anchored in the opening by means of suitable cement, indicated at 33. The outer end of this bolt is threaded for reception of a clamping nut 34 and a lock washer 35 and is arranged to extend through an opening 36 in the web portion 37 of a mounting bracket 38, which web portion 37 is adapted to bear against the rear face of casing 10, as indicated in Figs. 1 and 2.

Mounting bracket 38, the details of which are shown in the perspective view of Fig. 3, is comprised of any suitable metal having springiness and resistance to vibration fatigue failure. This bracket is formed with a substantially flat and relatively thin portion 39 having an upper reinforcing ridge 40 and a lower reinforcing ridge 41. In the outer end of portion 39 is a socket opening 42 disposed substantially in the plane of portion 39 and adapted to receive a terminal stud 43 of a transformer or like piece of electric apparatus and to rest upon the upper end of the terminal supporting bushing 44, as shown in Figs. 1 and 2.

Casing 10 is clamped, by means of bolt 32, nut 50 34 and washer 35, so that the rear face of the casing bears tightly against the lower face of web 37. This web is arranged so that it lies in a plane at an acute angle to the plane of the flat portion 39 of the mounting bracket or, in other 55

words, so that it lies in a plane at an angle of less than 90 degrees to a plane extending through terminal stud 43 normal to the plane of opening 42. As a result of this expedient, casing 10 is supported, as best shown in Fig. 2, so that it is tilted forward at an acute angle to a plane passing through the axis of terminal stud 43 so that arc gases discharged from the lower end of fuse holder 14 will not be directed straight down- 10 wardly on to the lower end of bushing 44 and the adjacent portion of the cover of the transformer 45 (see Fig. 4) to damage the bushing or cause short circuiting arc-over between conducting parts. The forward tilting of the casing also 15 prevents leakage of rain water into casing 10 when door 22 is normally closed and prevents the entrance of rain, sleet, and snow into the casing when the door is in its open dropped-out position previously referred to. Bracket 38 has 20 spaced apart flanges 46 projecting from the lower face of web portion 37 of the bracket and arranged to receive the cutout casing therebetween to prevent rotation of the casing relative to the bracket about bolt 32.

25 As a further result of the formation of the bracket as previously described, the flat portion 39 lies in a plane substantially transverse to the axis of fuse holder 14. Due to its relative thinness, portion 39 of the bracket flexes resiliently 30 upon recoil of the fuse holder due to fuse operation or upon slamming of the door, thus providing a cushioning effect to prevent damaging shock to the supporting bushing 44 which commonly is of insulating ceramic material relatively easily 35 damaged by shock. Reinforcing ridges 40 and 41 are arranged to give sufficient stiffness to the bracket for proper support of the cutout while at the same time permitting the desired flexibility of portion 39 of the bracket.

40 Also, in accordance with the teachings of my copending application, Serial No. 176,271 filed November 24, 1937, and assigned to the assignee of the present invention, it is preferable that bracket 38 be provided with a plurality of slots 45 47 communicating with socket opening 42 and extending radially of the opening with the slots arranged in pairs and the slots of each pair disposed diametrically opposite each other, as best shown in Fig. 3. These slots are arranged to receive a keeper element 48 extending through a transverse slot 49 in terminal stud 43 to prevent rotation of bracket 38 about the terminal stud. By reason of the plurality of pairs of slots 47, it is possible selectively to position the bracket 50 and the cutout casing attached thereto so that the door 22 is readily accessible from a transformer supporting pole 50 or similar mounting structure and so that the lower discharge end of fuse holder 14 is directed outwardly over the side 55 of the transformer, as indicated in Fig. 4. An added advantage of the forward tilting of the casing when the cutout is mounted as shown in Fig. 4, is that a service man is protected from injury by gases discharged from the lower end 60 of the cutout in case of fuse operation during servicing. With the arrangement described, the cutout casing may be mounted in any desired manner in different transformer installations wherein the supporting pole and terminal bushing 65 have different physical relationships with respect to each other and the transformer casing.

In an installation of the type diagrammatically illustrated in Fig. 4, the lower contact of the cutout is connected to the transformer terminal 70 stud through mounting bracket 38 while the up-

per contact has secured thereto, as by means of a screw 51, one end of a line lead indicated at 52. Also, contact 11 may have secured thereto one end of a lead 53 extending from a lightning arrester indicated at 54 as being mounted on the side of the transformer 45. Thus, there is provided a unitary transformer assembly embodying both overcurrent and overvoltage protection.

From the foregoing description, it will be seen that the switching device of my present invention provides a means for securing in outdoor installations, such as on rural type transformers and the like, an improved fusing protection with the advantages of the enclosed type fuse cutout, including superior insulation, safety to service 10 men, and weather protection, which advantages it is not possible to secure with the line suspension fuse cutouts and bushing mounted open type fuse cutouts of the type heretofore commonly employed. My invention provides also an improved 15 switching device of the enclosed type, which, while having the advantages above set forth, still is of such simple and low cost construction that it may be embodied to advantage with other protective equipment, such as a lightning arrester, 20 in a transformer assembly of the unit type so as greatly to facilitate the installation of the transformer assembly on a pole or other suitable supporting structure in the field.

What I claim as new and desire to obtain by 30 Letters Patent of the United States is:

1. The combination with an electric switching device of the enclosed type having an insulating housing with a pair of spaced terminal contacts therein and means for supporting in the housing 35 an electric switching element connected between said contacts, of a springy mounting bracket of electrically conductive material secured to said housing and having means for attachment to a bushing supported terminal stud of a transformer 40 or the like, and means providing electric connection between one of said contacts and said mounting bracket.

2. The combination with an insulating housing 45 for an electric switching device, of a contact mounted in the housing, an electrically conductive mounting bracket attached to the housing and provided with means for attachment to an electrically conducting support for the housing, and an electrically conductive element mechanically and electrically connected with said bracket 50 and extending into the housing, which said element is provided interiorly of the housing with means for pivotally supporting an electric switching 55 element for engagement with said contact.

3. The combination with an electric switching device of the enclosed type including an insulating housing comprised of a casing having an open front and a door movably mounted for closing said open front, of a mounting bracket having a substantially flat and relatively thin springy portion provided adjacent one end with a socket opening lying substantially in the plane of said flat portion and adapted to receive a supporting stud, said bracket having adjacent the other end of said first mentioned portion a web portion disposed at an acute angle to the plane of said first mentioned flat portion, and means securing said casing to said bracket with the rear face of the casing bearing against the underneath face of said web portion, whereby said open front of the casing is maintained in a plane tilted forward at an acute angle to the plane of said first mentioned flat portion and said socket opening.

4. The combination with an electric switching

75

75

device of the enclosed type having a housing of insulation with spaced contacts mounted therein and means for supporting an electric switching element connected between said contacts, 5 of a mounting bracket for said housing having an attachment portion arranged to bear against the rear face of said housing and a pair of arms projecting from said attachment portion in spaced relation to each other for receiving said housing 10 therebetween, and means for securing said housing in the seat provided by said attachment portion and projecting arms.

5. In an electric switching device, an enclosing housing of insulation, a pair of spaced contacts 15 mounted in the housing, hinge means for pivotally supporting an electric switching element in the housing connected between said contacts, and an electrically conductive mounting bracket for said housing having means for attachment to a 20 terminal stud of a transformer or the like, one of said contacts having an electrically conductive element extending exteriorly of said housing and connected to said bracket for securing the housing to the bracket.

25 6. In an electric switching device of the enclosed type, a housing of insulation, spaced contacts mounted in the housing and hinge means for pivotally supporting a switching element in the housing removably connected between the 30 contacts, one of the contacts having an electrically conductive mounting element extending exteriorly of the housing for attachment to a support for the housing.

35 7. In an electric switching device of the enclosed type, a housing of insulation and a pair of contacts mounted in the housing, one of which contacts is provided interiorly of the housing with means for pivotally supporting a switching element removably connected between the 40 contacts and said one contact having an electrically conductive mounting element extending exteriorly of the housing for attachment to a support for the housing.

45 8. In an electric switching device of the enclosed type a housing of insulation, spaced contact means mounted in the housing and a mounting member extending through a wall of the housing in fixed relation thereto, which said member is provided exteriorly of the housing 50 with means for attachment thereof to a support for the housing and is provided interiorly of the housing with means for pivotally supporting a switching element removably connected between said contact means.

55 9. In an electric switching device of the enclosed type, a housing of insulation, an upper contact mounted in the housing, and a lower contact mounted in the housing, which said lower contact is provided interiorly of the housing with 60 a hinge bracket for the pivotal support of an electric switching element and has an electrically conductive portion extending exteriorly of the housing for attachment to a support for the housing.

65 10. In an electric switching device of the enclosed type, a housing including an insulating casing having an open front, a contact mounted in the housing, and an electrically conductive bolt fixedly mounted in the rear wall of the housing in spaced relation to said contact, which bolt has a threaded portion extending exteriorly

of the housing for attachment thereof to a support for the housing and a portion extending interiorly of the housing provided with means for supporting an electric switching element for removable engagement with said contact.

5

11. An electric switching device including in combination an enclosing housing of insulating material, an electrically conductive mounting bracket for said housing having means for attachment to an electrically conductive supporting stud and having also a web portion arranged to bear against one of the walls of said housing, a pair of contacts mounted in said housing, one of said contacts having means for supporting an electric switching element in the housing connected between the contacts and having also a portion extending exteriorly of the housing and connected with said web portion for securing the housing to said bracket, and means carried by said bracket for preventing displacement of the 20 housing relative to the bracket.

15

12. In a housing for an electric disconnect switch, fuse cutout and the like, a box-like casing of insulation having top, rear and side walls and an open front, which open front provides for manipulation of an electric connection element to and from a connected position between spaced contacts mounted in the casing and which open front is adapted to be closed by a removable door, and upper and lower contacts mounted in 30 the casing in substantially fixed spaced relationship for removable engagement by an electric connection element, one of which contacts has an electrically conductive mounting element provided with means for mounting attachment 35 to an electrically conducting support for the casing.

25

13. In an electric switching device, a box-like insulating casing having top, rear and side walls and an open front providing for manipulation of 40 an electric connection element to and from connected position between spaced contacts mounted in the casing, a door for closing said open front, upper and lower contacts mounted in the casing in substantially fixed spaced relationship, one 45 of which contacts has an electrically conductive mounting element provided with means for mounting attachment to an electrically conducting support for the casing, and means for supporting an electric connection element in the 50 casing in connected position between said contacts, which said supporting means is arranged to provide for movement of an electric connection element relative to said contacts to a disconnected position.

55

14. In an electric switching device, a box-like insulating casing having top, rear and side walls and an open front, a door for closing said open front, an upper contact mounted in said casing, a lower contact mounted in the casing and having an electrically conductive mounting element provided with means for mounting attachment to an electrically conducting support for the casing, and means including said lower contact 60 arranged to support an electric connection element in the casing in connected position between said contacts and to provide for movement of the electric connection element relative to said contacts to a disconnected position.
